Attorney, Agent, or Firm—Sughrue, Mion, Zinn, Macpeak
& Seas, PLLC

[**] Term: 14 Years

[57] CLAIM

[21] Appl. No.: 62,937

The ornamental design for an electroacoustic transducer, as
shown and described.

[22] Filed: Dec. 5, 1996

DESCRIPTION

[30] Foreign Application Priority Data

Jun. 5, 1996 [JP] Japan 8-16589
Jun. 5, 1996 [JP] Japan 8-16590

[51] LOC (6) Cl. 14-01

FIG. 1 is a perspective view of the front, top and left side of
an electroacoustic transducer showing our new design;

[52] U.S. Cl. D14/222; D10/116

FIG. 2 is a front elevational view thereof;

[58] Field of Search D10/75, 104, 106,

FIG. 3 is a top plan view thereof;

D10/116-118, 121; D13/152, 156, 184,
199; D14/10, 107, 140, 222, 240; 324/156;
340/384.1, 384.3, 384.6, 384.7, 384.72,
388.1, 388.6, 390.1, 391.1, 392.1-392.5,
396.1, 407.1; 361/600, 679, 724, 829; 381/188-199;
367/175FIG. 4 is a left side elevational view thereof, the right side
being a mirror image thereof;

[56] References Cited

FIG. 5 is a bottom plan view thereof;

U.S. PATENT DOCUMENTS

FIG. 6 is a rear elevational view thereof;

D. 251,085 2/1979 Fanshawe ..... D14/222 X
D. 315,334 3/1991 Fujioka ..... D13/156 XFIG. 7 is a perspective view of the front, top and left side of
a second embodiment of FIG. 1; and,

FIG. 8 is a front elevational view of FIG. 7.

The undisclosed right, bottom and rear views of the second
embodiment are identical to the corresponding views of the
first embodiment.
